Specification for Design.

Patented Jan. 4, 1921.

Application filed June 15, 1920. Serial No. 389,242. Term of patent 14 years.

To all whom it may concern:

Be it known that I, JANE DEETER RIPPIN, a citizen of the United States of America, residing in the borough of Manhattan, city, county, and State of New York, have invented a new, original, and ornamental Design for Scarfpins, Breastpins, Hatpins, Buttons, Rings, Medallions, Badges, or Articles of Similar Nature, of which the following is a specification, reference being had to the accompanying drawing, forming a part thereof.

The figure is a face view of a breast pin, showing my new design.

I claim—

The ornamental design for a scarf pin, breast pin, hat pin, button, ring, medallion, badge, or article of similar nature, as shown.

In witness whereof I have hereunto signed my name.

JANE DEETER RIPPIN.
